HANDLED SUPPORT FOR CUPS, GLASSES,
AND OTHER CONTAINERSHarold Henry Robert Hanford, Vancouver,
British Columbia, Canada

Application September 23, 1939, Serial No. 296,258

3 Claims. (Cl. 294—27)

My invention relates to improvements in handled supports for such articles as cups, particularly paper cups, and containers, such as paper cartons and the like.

This is a continuation-in-part of United States Patent No. 2,194,898.

The object of the invention is primarily to provide a support of extremely low cost which is capable of encircling a paper cup or other container, which support is provided integrally with handle portions to facilitate the carrying of the container.

The invention consists of a strip of material slotted intermediate its length to provide container encircling members and having portions adapted to extend above the container to serve as carrying handles, as will be more fully described in the following specification and shown in the accompanying drawing, in which:

Fig. 1 is a view of a blank from which the support is made and having side portions to be used as handles.

Fig. 2 is a perspective view of the invention as applied to a carton having tapered sides or a carton provided with an upper rim.

Fig. 3 is a view of a modified form of blank provided with terminal end portions to serve as handles.

Fig. 4 is a perspective view of a cup fitted with the modification.

Fig. 5 is a perspective view of a carton fitted with the modification.

In the drawing like characters of reference indicate corresponding parts in each figure.

The numeral 1, see Figures 1 and 2, is a blank of the support preferably made of sheet material having a medial incision or slot 2 and a pair of side incisions 3 which define between the incisions 2 and 3 container encircling portions 4, and between the incisions 3 and the sides of the blank, handle portions 5. Diagonal creases 6 extend across the ends of the encircling portions 4 along which the support is adapted to be bent. Creases 7 are formed transversely across the side portions 5 at points remote from the encircling portions 4, upon which the handle portions are adapted to be bent. The creases 7 while shown as being remote from the ends of the encircling portions may be in any position to give whatever length of handle portion that may be desired. The end portions of the blank are numbered 8 and serve as connecting members between the handle portions 5 and the encircling portions 4.

In the modification, or the simpler form of

the invention as shown in Figures 3, 4 and 5, the blank is indicated by the numeral 10, and is incised or slotted intermediate its length as at 11 to provide encircling portions 12. Diagonal creases 13 indicated by dotted line, extend from the ends of the slot 11 to the marginal edges of the blank to facilitate folding. The end portions of the blank are indicated by the numeral 14 and are preferably wider than the intermediate portion to provide a pair of handles 15. The handles are preferably provided with openings 16 to enable the fingers to be passed through for carrying purposes.

In fitting the blank 1 to a container, the blank 15 is bent and the handle portions 5 are raised in an arc until the blank folds along the crease lines 7, then the encircling portions 4 are lifted intermediate their length and spread apart, causing the parts to fold at the creases 6. This latter movement disposes the encircling portions on their edges so that the container can be slipped in between them as shown.

The fitting of the blank 10 is done by spreading the encircling portions 12 in the manner above described and by raising the handles 15 to project above the rim of the container as shown in Figures 4 and 5.

If the device is to be fitted to a container which is neither provided with a projecting rim or tapered sides, tabs 17 would be pressed out of its side walls which would be engaged by the upper edge of the encircling portions 12 and thus prevent displacement of the assembled parts.

What I claim as my invention is:

35. 1. A handled support for containers such as paper cups and the like comprising an elongated strip of material having three substantially parallel longitudinal incisions extending intermediate its length to provide terminal portions, encircling portions and outer portions, said strip being creased to facilitate the encircling portions being spread apart to surround a container, and said outer portions being raised to form handles extending across the top of said container.

40. 2. A handled support for containers such as paper cups and the like comprising an elongated strip of material having an elongated incision along a medial portion of its longitudinal axis to divide said strip into narrow side strips connected to terminal portions, each of said side strips being divided longitudinally into inner and outer side strip portions, said side strips being creased adjacent the ends of the incision to facilitate bending the strip material for the inner and outer side strip portions to encircle the con-

45.

50.

tainer and for the terminal portions to project at right angles to the side strip portions.

3. A handled support for containers such as paper cups and the like comprising an elongated strip of material having an elongated incision along a medial portion of its longitudinal axis to divide said strip into narrow side strips connected to terminal portions, each of said side strips being divided longitudinally into inner and

outer side strip portions, said side strips being creased adjacent the ends of the incision to facilitate bending the strip material for the inner side strip portions to encircle the container, for the terminal portions to project upwardly of the container walls and for the outer side strip portions to be bent to form overlying handles for the container.

HAROLD HENRY ROBERT HANFORD.
